United States Patent Office

Des. 195,492
Patented June 18, 1963

195,492

DISPLAY RACK

Leonard J. Benne, Cleveland, Ohio, assignor to American Greetings Corporation, Cleveland, Ohio, a corporation of Ohio

Filed July 23, 1962, Ser. No. 71,012

Term of patent 14 years

(Cl. D80—9)

FIG. 1

In said drawings, FIG. 1 is a front perspective view taken from one side of a display rack showing my new design;

FIG. 2 is a rear perspective view thereof taken from the side opposite that shown in FIG. 1; and

FIG. 3 is a top plan view thereof.

I claim:

The ornamental design for a display rack, as shown.
